US0D1093716S

(12) **United States Design Patent** (10) **Patent No.:** **US D1,093,716 S**
(45) **Date of Patent:** ** *Sep. 16, 2025

(54) **SPOTLIGHT**

(71) Applicant: **Guangzhou Flame Light Electronic Technology Co., LTD**, Guangdong (CN)

(72) Inventor: **Zhikun Zhu**, Guangdong (CN)

(73) Assignee: **Guangzhou Flame Light Electronic Technology Co., LTD**, Guangdong (CN)

(*) Notice: This patent is subject to a terminal disclaimer.

(**) Term: **15 Years**

(21) Appl. No.: **29/977,601**

(22) Filed: **Dec. 9, 2024**

(30) **Foreign Application Priority Data**

Nov. 26, 2024 (CN) 202430747314.2

(51) **LOC (15) Cl.** **26-05**

(52) **U.S. Cl.**

USPC **D26/99; D21/622**

(57) **CLAIM**

The ornamental design for a spotlight, as shown and described.

DESCRIPTION

FIG. 1 is a perspective view of a spotlight showing my new design;

FIG. 2 is a perspective view thereof from another angle;

FIG. 3 is a perspective view thereof from another angle;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view in a condition of use; and, FIG. 11 is a perspective view in a condition of use from another angle.

The broken lines in the drawings show portions of the spotlight that form no part of the claimed design.

1 Claim, 11 Drawing Sheets
